ATTORNEYS

UNITED STATES PATENT OFFICE.

JESSE WILLIAM MILLER, OF RED WING, MINNESOTA.

HEEL-TREAD PAD FOR HORSESHOES.

Application filed June 11, 1924. Serial No. 719,412.

To all whom it may concern:

Be it known that I, JESSE W. MILLER, a citizen of the United States, and a resident of Red Wing, in the county of Goodhue and State of Minnesota, United States of America, have invented new and Improved Heel-Tread Pads for Horseshoes, of which the following is a full, clear, and exact description.

This invention has relation to resilient tread pads, and has particular reference to a resilient heel tread pad for horseshoes, the same being an improvement over my prior United States Patent No. 1,492,525, issued April 29, 1924.

15 The present invention comprehends a heel tread pad which is particularly designed for use in connection with drive calk shoes and is capable of adjustment to fit the heels of shoes of various widths.

20 More specifically the present improvement relates to a heel tread pad consisting of a pair of transversely arranged pad body sections and an improved form of connection therebetween which serves to simplify the construction and to minimize the cost of 25 production.

With the above recited and other objects in view, the invention resides in the novel construction set forth in the following specification, particularly pointed out in the appended claims, and illustrated in the accompany drawings, it being understood that the right is reserved to embodiments other than those actually illustrated herein to the full extent indicated by the general meaning of the terms in which the claims are expressed.

30 In the drawings—

Figure 1 is a bottom plan view of a horseshoe with a tread pad constructed in accordance with the invention, in applied position;

Fig. 2 is a longitudinal sectional view therethrough taken approximately on the line indicated at 2—2 in Fig. 1;

Fig. 3 is a perspective view of the pad removed; and

Fig. 4 is an enlarged sectional view therethrough, taken approximately on the line 4—4 of Fig. 3.

Referring to the drawings by characters of reference, A designates a horseshoe of the drive calk type which is formed at its front or toe portion and adjacent its rear end or heel portions with calk openings B. As illustrated the usual drive toe calk C is driven into the openings B at the toe portion. In lieu of driving calks at the rear or heel

portion of the shoe, the heel tread pad attachment constituting the present invention, is employed. In the present invention the pad body consists of a pair of transversely arranged identically constructed sections 10 which are preferably constructed of a suitable yieldable or cushioning material such as rubber. The sections 10 in the present instance are connected by an elastic web 11 which is preferably of lesser thickness than the sections 10 which may or may not be formed integral therewith, and the lower surface of which connecting web is disposed in a plane above the lower surface of the pad 15 body sections, as clearly illustrated in Figs. 2, 3, and 4 of the drawings. Each of the sections has embedded therein the headed end 12 of an upwardly projecting tapered stud 13 which is designed to be driven into the calk 20 openings B at the heel portion of the shoe whereby the heel tread pad is associated with the shoe. The elastic connecting web 11 serves to permit relative transverse adjustments of the sections 10 in order to compensate 25 for variations in the spacing of the calk openings B. In applying the heel tread pad to the shoe, one of the studs 13 is engaged in one of the heel calk openings B and the connecting web 11 is stretched sufficiently to permit of the engagement of the other stud 13 in the opposite heel calk opening B, after which the studs are hammered 30 home to operatively associate the sections with the shoe. The connecting web 11 then 35 serves as a means for holding the sections 10 in alignment to prevent twisting or turning 40 of the same when the shoe is in use.

I claim:

1. The combination with a horseshoe provided with drive calk receiving openings in the rear end thereof, of a heel tread pad therefor comprising a pair of transversely arranged pad body sections, each section having an upstanding element for frictional driving engagement in the calk receiving openings, and an elastic connection between said sections for permitting relative lateral movement therebetween to vary the spacing between said elements.

2. The combination with a horseshoe provided with drive calk receiving openings in the rear end thereof, of a heel tread pad therefor comprising a pair of transversely arranged pad body sections, each section having an upstanding element for frictional driving engagement in the calk receiving

- openings, and a flexible elastic connection between said sections for permitting relative lateral movement therebetween to vary the spacing between said elements.
5. The combination with a horseshoe provided with drive calk receiving openings in the rear end thereof, of a heel tread pad therefor comprising a pair of transversely arranged pad body sections, each section having an upstanding element for frictional driving engagement in the calk receiving openings, and a flexible elastic connecting web between said sections for permitting relative lateral movement therebetween to vary the spacing between said elements.
10. The combination with a horseshoe provided with drive calk receiving openings in the rear end thereof, of a heel tread pad therefor comprising a pair of transversely arranged pad body sections, each section having an upstanding element for frictional driving engagement in the calk receiving openings, and a flexible elastic connecting web between said sections for permitting relative lateral movement therebetween to vary the spacing between said elements.
15. The combination with a horseshoe provided with drive calk receiving openings in the rear end thereof, of a heel tread pad therefor comprising a pair of transversely arranged pad body sections, each section having an upstanding element for frictional driving engagement in the calk receiving

openings, and a flexible elastic connecting web between said sections for permitting relative lateral movement therebetween to vary the spacing between said elements, said web being of lesser thickness than the pad body sections.

20. The combination with a horseshoe provided with drive calk receiving openings in the rear end thereof, of a heel tread pad therefor comprising a pair of transversely arranged pad body sections, each section having an upstanding element for frictional driving engagement in the calk receiving openings, and a flexible elastic connecting web between said sections for permitting relative lateral movement therebetween to vary the spacing between said elements, the lower surface of said connecting web being disposed above the lower surface of the pad body sections.

JESSE WILLIAM MILLER.
